Specification of Letters Patent.

Patented Feb. 9, 1915.

Application filed November 5, 1914. Serial No. 870,388.

To all whom it may concern:

Be it known that we, WILLIAM C. BOLLWINKEL and EVERETT C. KLINE, citizens of the United States, residing at Norwood, in the county of Hamilton and State of Ohio, have invented certain new and useful Improvements in Safes, of which the following is a specification.

Our invention relates to the construction of safes and particularly to improvements in the construction of the parts by which conical, cylindrical or similarly shaped safe doors, which are rotated to screw into and out of closed position, are mounted in closed position and guided into and out of such position. In safes of this character as previously constructed, a helical machined and ground metal key or thread has been forced into position in a correspondingly shaped lead formed in the jamb of the door, this key engaging within a corresponding lead formed in the conical or cylindrical ground surface of the door. In our construction, a turned and finished key is mounted in the helical lead or key way formed on the door and secured therein, this key engaging within a corresponding lead formed in the jamb. The key or metal thread member is secured in position in the lead of the door by means of securing devices extending from the interior of the door into the rear portion of the key. In a door of preferred construction, which is cast of manganese steel with a cored interior recess having an opening at the rear of the door and having a tapered or annular flange surrounding this recess, inserts of soft metal will be provided extending through the flange of the door to the inner surface of the lead formed on the exterior of the flange. Holes are drilled through these soft metal inserts and when the turned and finished key has been forced into position in the lead of the door, bolts or screws are passed through the drilled holes in the soft metal and into corresponding tapped holes in the rear face of the key thereby securely holding the key or thread in place.

In order that a clearer understanding of our invention may be had, attention is hereby directed to the accompanying drawings forming part of our invention and illustrating a preferred embodiment thereof.

In the drawings, Figure 1 represents a partial section through the jamb of a safe

with the door mounted in position therein, and Fig. 2 represents a partial section through the door showing the method of securing the key in position thereon as described.

Referring to the drawings, the door 1 is illustrated as seated within the jamb 2, the surface 3 of the door and the corresponding surface of the jamb being illustrated as conical. The lead 4 is ground into the surface 3 of the jamb, at any desired angle or pitch, and the door is provided with a corresponding lead. The door and the jamb member of the safe are formed of cast manganese steel or of other metal which may prove satisfactory for the purpose. The door as cast is provided with a conical flange 5 surrounding an inner space 6, the lead on the door being cored, and ground out in an approved manner to a given finished size. The helical key 7 is made of some suitable material of machinable nature, preferably vanadium steel. This key is turned as a single piece and finished to fit into the lead ground in the safe door. In manufacturing the parts described, the jamb and the external surface of the door are ground on an angle to the desired shape and are then finished by means of slush grinding. After this operation, the key 7 is then forced into position and attached by the means referred to. A series of soft metal parts 8, which we have referred to as soft metal inserts, are provided extending at intervals through the flange 5 of the door, extending through the same to the inner edge of the lead formed in the exterior surface 3 of flange 5. These soft metal portions may be inserted into cored openings formed when the door was cast. Holes are drilled through these inserts and the key 7 is provided with a corresponding number of tapped holes so that when the key has been placed in position and adjusted with the tapped holes of the key in line with the openings extending through the soft metal inserts, the bolts or screws 9 may be extended through the soft metal inserts and screwed into the key securely attaching the latter in position.

If desired, a slight recess may be ground on the step of the jamb of the safe and filled with a rubber or other suitable packing 10, to form a seat for the door in case the slush grinding of the door and jamb has not resulted in the formation of a sufficiently close

joint. When the door has been swung into place, it may be caused to revolve by usual means, not illustrated, such as a pinion and gear so as to force the door into the tapered 5 jamb to form a close contact between the door and the jamb.

It will readily be understood that our invention provides a construction in which the coacting parts may be readily and effectively ground so as to operate with the close contact required in high class safe construction, the key also being very readily mounted in position in the lead of the door, our invention also taking advantage of the 10 central cored recess of the door to extend screws or other securing devices from the same through the flange of the door into the key.

Having described our invention, what we 20 claim as new therein and desire to secure by Letters Patent of the United States is:

1. In a safe, the combination of a body member having a conical jamb, having a helical lead ground therein, a door having 25 an inner recess and a conical surface having a helical ground lead corresponding to that of the jamb, a helical key positioned in the lead of the door and adapted to engage with-

in the lead of the jamb, and a plurality of securing devices extending from said recess through portions of said door into said key, substantially as set forth.

2. In a safe, the combination of a jamb member having an inner surface of circular cross-section, having a helical lead formed 35 therein, a door of hard cast metal having a flange portion, the outer surface of which is adapted to seat within said jamb surface, said door having a helical lead formed in the outer surface of said flange portion corresponding to the lead of the jamb, a helical metal key positioned in the lead of the door and adapted to engage within the lead 40 of the jamb, soft metal inserts extending from the interior of said flange portion to 45 the lead in the door, and screws extending from the interior of the door through said soft metal inserts into said key, substantially as set forth.

This specification signed and witnessed 50 this 1st day of November, 1914.

WILLIAM C. BOLLWINKEL.
EVERETT C. KLINE.
